Primary Examiner — Mitchell I. Siegel*Assistant Examiner* — Bryan N. Melvin*(74) Attorney, Agent, or Firm* — MILLEN, WHITE, ZELANO & BRANIGAN, P.C.; Ryan R. Pool(57) **CLAIM**

The ornamental design for an electronic device, as shown and described.

DESCRIPTION

FIG. 1 illustrates a front perspective view of an electronic device showing our new design;
FIG. 2 illustrates a front elevational view thereof;
FIG. 3 illustrates a rear elevational view thereof;
FIG. 4 illustrates a right side elevational view thereof;
FIG. 5 illustrates a left side elevational view thereof;
FIG. 6 illustrates a top plan view thereof; and,
FIG. 7 illustrates a bottom plan view thereof.
The broken lines in the drawings illustrate portions of the electronic device that form no part of the claimed design.

1 Claim, 7 Drawing Sheets(56)
